(57) **CLAIM**

The ornamental design for a helmet jaw portion, as shown and described.

DESCRIPTION

FIG. 1 is a perspective view from the front and left side of a helmet jaw portion showing our new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.

Throughout the Figures, the broken line showing indicating structure forms no part of the claimed design.
